UNITED STATES PATENT OFFICE.

ADELBERT HOWARD MACRONALD, OF PORTLAND, MAINE, ASSIGNOR TO THOMAS LAUGHLIN COMPANY, OF PORTLAND, MAINE, A CORPORATION OF MAINE.

LINK.

No. 866,151.

Specification of Letters Patent.

Patented Sept. 17, 1907.

Application filed April 30, 1907. Serial No. 371,176.

To all whom it may concern:

Be it known that I, ADELBERT HOWARD MACRONALD, a citizen of the United States, residing at Portland, in the county of Cumberland and State of Maine, have 5 invented certain new and useful Improvements in Links, of which the following is a specification, reference being had thereto to the accompanying drawing.

This invention relates to improvements in links, and more particularly to that type of link illustrated in the 0 Thompson patent No. 193,295, and the Laughlin patent No. 774,189.

The type of link referred to consists generally of two substantially C-shaped members, the connecting portions of each of which are solid, while the ends thereof 15 are tapered to accommodate each other and maintain a uniform thickness with the solid connecting portions of the two members; and said members when reversed overlying each other in forming the completed link and having interfitting lugs and recesses, and interlocking projections at the center of each end of the link, the opposing surfaces of which are substantially at right angles to the axis of the link to prevent the ends from spreading, these last mentioned interlocking projections being suggested by the Laughlin patent referred 20 to, as an improvement upon the earlier Thompson link.

While the Laughlin link above mentioned has proved a decided advance in the art and possesses all of the merits claimed in its behalf, I have found by experience that a separable link of this character has a tendency to break at the extreme apertured ends of the C-shaped members, which ends, owing to the tapering of the same, are very thin and correspondingly weak, as compared to the other portions of the link. Hence the 30 present improvements are directed to the reinforcing 35 and strengthening of these apertured ends of the link members.

A convenient embodiment of the invention embraces a sectional link having overlapping split end portions thinned at the extremities, said extremities 40 being apertured and having bosses projecting inwardly therefrom around the apertures to fit into complementary seats in the opposite member of the link, said last mentioned member also having lugs projecting outwardly from said seats and fitting into the apertures of 45 said thin extremities.

The details in the construction and arrangement of parts will be apparent from the detailed description hereinafter contained, when read in connection with the accompanying drawing forming part hereof, and 50 wherein said convenient embodiment of the invention is illustrated.

In the drawing: Figure 1 is a perspective view of the link. Fig. 2 is an elevation of one of the link members,

and this view will suffice for both, inasmuch as they are exactly the same. Fig. 3 is an edge view of the link member shown in Fig. 2, Fig. 4 is a transverse sectional view taken on a curved line through the end of the link indicated by dotted lines in Fig. 1, and Fig. 5 is a detail section.

Referring more specifically to the drawings wherein like reference characters refer to corresponding parts in the several views, A A represent the two members of the link, they being of substantially C-shape and of like formation and contour, whereby either may be inverted and superposed upon the other to form a completed link of approximately uniform thickness throughout. Each of these C-shaped members is provided with a solid connecting portion B and beveled or tapering ends C leading from said connecting portion and gradually decreasing in thickness to the extremities thereof, which extremities, as best seen in Figs. 3 and 4, are very thin as compared to the thickness of the remaining portions of the link member. The opposing surfaces of the tapering ends of the link members are formed with interlocking projections D, the abutting walls of which are substantially at right angles to the axis of the link to prevent the ends from spreading. The extremities of the ends are apertured as at E for the reception of lugs F disposed near the solid connecting portions B of the link members, whereby to interlock with the extreme ends of said members.

To reinforce and strengthen the thin apertured extremities heretofore referred to, said extremities are formed on their inner surfaces with enlargements or bosses G arranged to fit into and snugly engage complementary recesses H in the opposite member of the link, which said recesses surround the lugs F.

From the foregoing description, it will be apparent that a link made in keeping with the present invention will be in general characteristics the same and possess 90 all of the advantages of the standard split link, while having the additional advantage incident to the substantial strengthening of the only existing relatively weak portions of the link.

I claim:—

A link consisting of separate members having overlapping portions, said overlapping portions being apertured and provided with lugs fitting said apertures whereby to interlock the members, the lugs being surrounded by recessed portions, and the apertures by bosses fitting said recesses.

In testimony whereof I affix my signature in presence of two witnesses.

ADELBERT HOWARD MACRONALD.
